[57] **CLAIM**

The ornamental design for a combined barbecue and cart therefor, as shown and described.

DESCRIPTION

FIG. 1 is an isometric view of a combined barbecue and cart therefor showing my new design;

FIG. 2 is a top plan view thereof;

FIG. 3 is a bottom plan view thereof;

FIG. 4 is a front elevational view thereof;
FIG. 5 is an elevational view of the right side, the left side view being a mirror image thereof;

FIG. 6 is an isometric view of the barbecue, with the cart omitted for clarity of illustration only;

FIG. 7 is a top plan view thereof as shown in FIG. 6;

FIG. 8 is an elevational view of the left side thereof;

FIG. 9 is a bottom plan view thereof;

FIG. 10 is an elevational view of the right side thereof;

FIG. 11 is a front elevational view thereof; and

FIG. 12 is a rear elevational view thereof.

FIG. 1.

FIG. 2.

FIG. 3.

FIG. 4.

FIG. 5.

FIG. 6.

FIG. 7.

FIG. 8.

FIG. 9.

FIG. 10.

FIG. 11.

FIG. 12.
